UNITED STATES PATENT OFFICE.

FRANTIŠEK JANEČEK, OF PRAGUE, CZECHOSLOVAKIA.

HAND GRENADE.

Application filed July 1, 1921. Serial No. 481,944.

(GRANTED UNDER THE PROVISIONS OF THE ACT OF MARCH 3, 1921, 41 STAT. L., 1313.)

To all whom it may concern:

Be it known that I, FRANTIŠEK JANEČEK, a citizen of the Czechoslovak Republic, residing at Prague, Czechoslovakia, have invented certain new and useful Improvements in Hand Grenades (for which I have filed application in Czechoslovakia, June 26, 1920), of which the following is a specification.

My invention relates to a hand-grenade which irrespective of the way in which it comes in contact with the object aimed at and irrespective of the condition of this object, is exploded merely by the action of a spring which remains in a compressed state during the rotation of the thrown grenade under the action of the centrifugal force of a freely movable body or weight. When the grenade reaches its aim, no matter whether the same be solid or liquid, and comes to rest, the action of the centrifugal force of the weight upon the spring ceases and the compressed spring suddenly released rebounds and explodes the grenade by the means hereinafter described.

In the drawings affixed to this specification and forming part thereof a grenade embodying my invention is illustrated by way of example in two modifications which mainly differ in outer appearance.

In the drawings—

Fig. 1 is a longitudinal section of a hand-grenade with egg-shaped shell,

Fig. 2 is a cross-section thereof,

Fig. 3 a longitudinal section of the internal portion of the grenade unlocked during the flight.

Fig. 4 is a cross-section thereof, and

Fig. 5 is a longitudinal section of a hand-grenade in the form of a comparatively long cylinder and

Fig. 6 a cross-section thereof.

Referring to Figs. 1-4, the hand-grenade has an egg-shaped shell 2 charged with explosives, which consists of sheet-metal halves inserted in one another or which may be cast in one piece. Into this shell 2 is inserted from the top and fixed by expansion or otherwise the fuse 4, having the shape of a hollow cylinder. This fuse 4 is furnished at the bottom with a perforated internal nut 5, against which the explosion cap 7 is drawn by means of another nut 5¹. In the interior of the fuse 4 the weight 8

and the priming shell 9 are movably disposed. The weight 8 is furnished with a fixed needle 19, the upper end of which extends into a central recess of the weight 8 and is there loosely guided within the bore of a cone 24 fixed in the top 4¹ of the fuse. 55 60

Between a collar on the lower end of the weight 8 and the top 4¹ of the fuse 4 a helical spring 21 is inserted under moderate tension. The upper annular surface of the weight 8 is countersunk and provided with an undercut groove 23 into which a heart-shaped spring 22 is fitted, the free ends of which are bent towards the inside and grip the cone 24 between them, (Fig. 4). The cone is provided near its upper end with a groove 70 75 25 adapted to be engaged by the ends of the spring 22.

Between the priming shell 9 and the weight 8 a conical pin 18 is intercalated. The point of this pin is rounded and its base is cylindrical. With this cylindrical portion the pin 18 is inserted in a bore or recess 17 of the shell 9. With its rounded point the pin 18 abuts against the front of the weight 8 and in this position prevents the needle 19 from reaching the percussion cap 10. 80

The explosion of the grenade is brought about in the following manner: the grenade is thrown in such manner that during its flight it rotates around its transverse axis $x-x$. During the rotation of the thrown grenade the priming shell 9 owing to the centrifugal force is pressed against the nut 5, while the weight 8 moves outwards 90 against the resistance of the spring 21, until the ends of the heart-shaped spring 22 snap into the groove or neck 25 of the locking cone 24. The pin 18 which under the action of the centrifugal force moves in the same 95 direction as the weight 8 leaves the bore 17 of the priming shell and loosing its guide tilts over and lies flat against the weight, so that when the rotation of the grenade ceases (by impact with the object aimed at) 100 the compressed spring 21 throws the weight 8 together with the needle 19 against the priming shell 9, the needle 19 striking the percussion cap 10, the flame of which passes through the bore of the nut 5 into the explosion cap and explodes this and thereby 105 the charge of the grenade.

In order to set the grenade rotating about

its transverse axis $\alpha-\alpha$ when fired from an extension of the barrel of a gun or the tube of a cannon, the lower portion of the shell of the grenade is provided with an expanded or cast-on nose 38, for the guidance of which the gun barrel extension or the like is provided in its interior with a groove 40 which at the mouth ends into an inclined plane 41. The grenade fired from the gun 10 will be given a turn at the moment when it has issued from the larger part from the extension 42 of the barrel and its nose 38 runs up the inclined plane 41 at the end of the groove 40, which causes a rotation of the 15 grenade around its transverse axis during its further flight.

In order to make the grenade also suitable for being thrown by hand without the aid of a handle, a projection 39 with a roughened surface is provided on the rear sphere of the shell 2 on which the index-finger finds a hold, whereby the desired rotation of the grenade about its transverse axis $\alpha-\alpha$ can be initiated.

25 In order to render the grenade safe for transport, it is fitted with a key 43 which is screwed into a tapped hole of the cone 24 and presses upon the rear-end of the needle 19 and thereby also on the weight 8 20 which transmits the pressure to the pin 18 and securely holds it in its operative position and prevents it from accidentally tilting. The key 43 is locked against unscrewing by a depending spring 44 which engages 35 with its free end the fluted edge of the top 41 of the casing or cartridge 4.

The hand-grenade illustrated in Figs. 5 and 6 is distinguished from the before-described one, mainly by its external appearance, inasmuch as its casing is cylindrical and comparatively long, in order to provide a good grip for the hand and to facilitate the imparting of the necessary transverse rotation when throwing it.

45 Into the shell 2 of the grenade charged with explosives, extends the casing 4, in which the priming shell 9 is contained. The shell 2 is extended upwards by a somewhat reduced shell 2¹ in which the weight 8 50 with its needle 19 and the spring 21 are disposed. Between the weight 8 and the priming shell 9 the conical pin 18 is arranged. The free end of the shell 2¹ is expanded to afford a comfortable handle for throwing 55 the grenade. Within this expanded open part is provided the safety-key 43 for locking the grenade during transport.

I claim:

1. In a device of the kind described in combination, a guide sleeve, an igniting device and a striker pin carrier in said sleeve, the striker pin extending rearwards into a cavity of said carrier, a locking cone extending into said cavity and a stopper screwed into said cone so as to press against the rear end of said pin, resilient means tending to force said device and said carrier against one another and a spacing pin loosely inserted in an indenture of one and resting against the surface of the other member. 60 65 70

2. In a device of the kind described in combination, an igniting device, a striker body, a common guide sleeve surrounding said device and body, resilient means tending to force said members against one another, a spacing pin loosely inserted in an indenture of one and resting against the surface of the other member, an egg-shaped shell surrounding all said parts, a lateral projection on said shell and a barrel adapted to surround said shell and provided with a longitudinal groove ending short of the outer end of said barrel and adapted to embrace said projection. 75 80 85

3. In a device of the kind described in combination, a guide sleeve, a striking pin carrier in said sleeve, a locking cone extending into an axial cavity of said carrier, resilient means tending to force said carrier away from said cone and a substantially heart-shaped spring fixed to the rear end of said carrier and adapted to resiliently embrace an annular groove provided in the circumference of said cone. 90 95

4. In a device of the kind described in combination, a guide sleeve, a striking pin carrier in said sleeve, a locking cone extending into an axial cavity of said carrier, resilient means tending to force said carrier away from said cone, an igniting device at the other end of said sleeve, a spacing pin loosely inserted between said device and said carrier, a striker pin loosely inserted in said carrier and extending into an axial boring of said cone and a key screwed into said boring so as to act as an abutment for said pin. 100 105

In testimony whereof I affix my signature.

FRANTIŠEK JANEČEK.
